(57) **CLAIM**

The ornamental design for a caliper for brake disc as shown and described.

DESCRIPTION

FIG. 1 is a top, front, left side perspective view of a caliper for brake disc showing my new design;

FIG. 2 is a left side elevation view thereof;

FIG. 3 is a rear elevation view thereof;

FIG. 4 is a front elevation view thereof;

FIG. 5 is a top plan view thereof;

FIG. 6 is a bottom plan view thereof;

FIG. 7 is a top, rear, right side perspective view thereof; and,
FIG. 8 is a top, front, right side perspective view thereof.
The broken lines illustrate portions of the caliper for brake disc that form no part of the claimed design.

1 Claim, 8 Drawing Sheets

FIG. 2

FIG. 3

FIG 4

FIG. 5

FIG. 6
